LIQUID CONTAINER CLOSURE AND DISPENSING MEANS

Elmer Lipman, 550 Woodland Drive, South Lyon, Mich.
Filed Mar. 13, 1961, Ser. No. 95,148
1 Claim. (Cl. 222—209)

This invention relates to liquid container closure and dispensing means selectively sealed for shipping and storage and open to atmosphere for dispensing liquid.

Combination container caps and dispensing means have been employed heretofore, however, the several devices of the prior art have not proven entirely satisfactory inasmuch as they are complicated in design and construction, expensive to manufacture, difficult to use, difficult to maintain in use, and not positive in sealably closing the container for shipping and storing.

With the foregoing in view, the primary object of the invention is to provide a container cap and dispensing means which is simple in design and construction, inexpensive to manufacture, easy to use, easy to remove, and which is positive in sealing off the container during periods of shipping and storage.

An object of the invention is to provide separate liquid supply stem means and separate cap dispensing means which normally intercommunicate automatically when mounted on a container and which are automatically disconnected and sealed when a sealing disc is disposed between them.

An object of the invention is to provide a cap having liquid atomizing or pump means for dispensing liquid from the container.

An object of the invention is to provide stem means insertable in the container normally automatically communicating with the dispensing means of the cap for supplying liquid from the container to the cap dispensing means.

An object of the invention is to provide a spring pressed hollow plunger in the stem portion adapted to press against a cap aperture in sealing relationship thereto for communicating liquid to the cap.

An object of the invention is to provide a removable sealing disc between the cap and stem portion for positively sealing the container during periods of shipping and storage.

These and other objects of the invention will become apparent by reference to the following description of a container cap and selectively sealable dispensing means embodying the invention taken in connection with the accompanying drawing in which:

FIG. 1 is a vertical cross-sectional view of a container having the dispensing cap and communicating stem showing the positive sealing disc in position.

FIG. 2 is a view similar to FIG. 1 showing the sealing disc removed.

FIG. 3 is a cross-sectional view of the device seen in FIG. 2 taken on the line 3—3 thereof; and

FIG. 4 is a view similar to FIG. 1 showing different dispensing or pump means.

Referring now to the drawing wherein like numerals refer to like and corresponding parts throughout the several views, the dispenser cap, communicating stem, and positive closure disclosed therein to illustrate the invention comprises a cap 10 disposed on a container 11 communicating to the liquid content thereof through a hollow stem assembly 12 leading to a cap aperture 13 which leads to a dispensing opening 14. In FIG. 1, this communication is interrupted by a positive sealing disc 15. FIGS. 2 and 3 show communication between the stem and cap as permitted by removal of the disc 15.

More particularly, the cap 10 comprises a body 20 having a bottom socket portion 21 equipped with internal

2

threads 22 for threading on a container neck 23 and a wall 24 overlying a container neck top 25. The cap 10 also has a top cavity above the wall 24 including a transverse bore 26 housing an insert 27 which is equipped with an annular flange 28 at its inner end sealing with the bore 26. The insert 27 also has an annular flange 29 at the outer end sealing with the bore 26. This creates a chamber 30 radially between the bore 26 and the insert 27 and axially between the flanges 28 and 29. The insert has a transverse aperture 31 communicating to the chamber 30 which is in communication with the cap axial aperture 13; the top cavity is surmounted by a depressable bulb 32 so that upon manually depressing the bulb, air travels outwardly from the top cavity through the insert 27 past the insert aperture 31 creates a low pressure condition so as to draw air and liquid from the chamber 30 and from the aperture 13.

The stem assembly 12 includes a socket 40 surmounted by an annular flange 42 resting on the container neck top 25 and effects a positive seal between the cap wall 24 and the bottle neck top 25. A spring 43 is disposed in the socket 40 and a hollow plunger 44 rests on the spring and is urged upwardly thereby into sealable contact with the cap wall 24 and it is to be noted that the plunger 44 has an axial aperture 45 in communication with the cap wall aperture 13 and that the plunger aperture 45 acts as a continuation of the hollow tubes 46 and 47 which lead to the liquid in the bottom of the container 11.

During periods of shipping and storage the sealing disc 15 is disposed between the cap wall 24 and the annular flange 42 so as to prevent communication between the tube assembly 12 and the cap aperture 13. Due to the fact that both the annular flange 42 and the sealing disc 15 are made of sealing material, such as polyethene, a positive seal exists between the cap and the container top 25.

During periods of shipping and storage the sealing disc remains in place and upon the customer desiring to use the contents of the bottle, he opens the device by removing the cap 10 and extracts the sealing disc 15 therefrom so that upon replacing the cap 10 the spring 43 urges the plunger 44 upwardly into sealing relationship with the cap wall 24 as seen in FIG. 2 thereby establishing communication between the liquid in the bottom of the container 11 and the dispensing aperture 14.

When the user then depresses the bulb 32, air is expelled through the insert 27 past the insert orifice 31 which draws liquid from the bottle through the orifice 31, chamber 30, cap aperture 13, plunger aperture 45, and the tubes 46-47 as the air rushing past the insert aperture 31 lowers the pressure in the chamber 30 thereby drawing liquid upwardly and when the liquid passes through the aperture 31 it is combined with the air rushing therethrough and is dispensed as a spray.

FIG. 4 shows another type of atomizing or liquid dispensing apparatus and may be combined with the stem assembly and sealing disc and it is obvious that the device may be modified with the spring pressed plunger integrated in the cap so as to press down against an aperture in the flange 42, however with the device as integrated, the cap can be positioned at a low level because the length of the socket 40 is absorbed by being disposed in the container neck 23.

The inventive device with these features constitutes a compact, durable, and neat appearing mechanism easily operated to seal a container for shipping and storage and easily conditioned for use by simply removing the sealing disc from its interrupting position between the stem assembly and the cap 10. With the invention the manufacturer saves the cost of individual sealing and dispensing caps and the cost of special boxes and cartons which were heretofore required.

Although but a single embodiment with one modification has been shown and described in detail, it is obvious that many changes may be made in the size, shape, detail, and arrangement of the various elements of the invention within the scope of the appended claim.

I claim:

Container closure and liquid dispensing apparatus for selectively sealably closing a container during shipping and storage to prevent leaking and evaporation and for selectively permitting container communication to atmosphere to permit liquid dispensing during use comprising a cap demountably mountable on a container neck having a wall exerting sealing force towards a container neck top; said cap having an axial aperture through said wall; dispensing means on said cap communicating with said cap aperture, a hollow stem disposable in a container neck opening having a bottom liquid conducting portion for leading to a container bottom and a top socket portion surrounded by an annular flange for resting on the top of a container neck as a support element for said stem and as a sealing element between said cap wall and a container neck top, a spring disposed in said socket, an axially hollow plunger disposed in said socket resting on said spring and urged upwardly thereby to effect sealing relationship with said cap wall in communication with said cap wall aperture to establish communication between said stem and said cap dispensing means to atmosphere to effect delivery of container liquid for use, and an easily removable sealing disc disposed between said stem flange and said cap bottom wall depressing said plunger against said spring and sealing off communication between said stem and said cap during periods of shipping and storage; said sealing disc being easily removable by removing said cap from a container; said device upon removal of said sealing disc and

remounting said cap on a container automatically conditioning itself for use with said spring urging said plunger into sealing relationship with said cap and said stem flange sealing between said cap and a container neck top; said dispensing means including said cap having a hollow transverse bore above said wall; a hollow tubular insert in said bore having outer and inner flanges sealing with said bore and a reduced intermediate portion between said flanges spaced from said bore creating a chamber therebetween, and a transverse aperture in said insert adjacent said outer flange communicating between said chamber and the hollow interior of said insert; said cap wall axial aperture communicating with a container as stated and also leading to said chamber intermediate said insert flanges; said cap body having a top cavity; a depressable bulb on said cap over said top cavity; said top cavity communicating through said hollow insert to atmosphere; manual depressing of said bulb expelling the air in said top cavity through said hollow insert venturi wise past said insert transverse aperture leading to said chamber to draw liquid from a container via said chamber, said wall aperture, and said liquid conducting means to expel combined air and liquid in a spray from said insert.
